UNITED STATES PATENT OFFICE.

THOMAS J. McDONALD, OF PHILADELPHIA, PENNSYLVANIA.

WASHING MACHINE.

Application filed March 2, 1926. Serial No. 91,760.

This invention relates to washing apparatus, and more particularly to improvements in a portable washing and drying machine.

The primary object of the invention is to provide a tilttable washing machine with supporting means movable with the machine and capable of positively maintaining the same in different positions during the washing and drying operations.

Another object of the invention is to provide means associated with the cover for supporting the outer end of the rotatable drum.

The invention further embodies a washing machine which is simple, light and compact in construction; which can be readily mounted on a wash tub, stand or the like; and is economical and efficient in operation.

Referring to the drawings wherein is shown a preferred embodiment of the invention:

Fig. 1 is a side elevation showing the machine mounted on a tub, and in the washing position.

Fig. 2 is a side elevation showing the machine in the drying position.

Fig. 3 is a vertical sectional view of the machine.

Fig. 4 is a longitudinal sectional view taken substantially along the line 4—4 of Fig. 3 looking in the direction of the arrows.

Fig. 5 is a fragmentary sectional view of a modified form of the invention.

Fig. 6 is a fragmentary sectional view of a further modification.

Fig. 7 is a side elevation of another modified form of the invention.

Fig. 8 is a sectional view taken substantially along the line 8—8 of Fig. 7.

Fig. 9 is a fragmentary sectional view of a further modification.

Referring to the drawings, in which like numerals indicate like parts in the several views, 10 denotes a metallic receptacle or container, preferably of cylindrical form, that has an annular bead 11 at its outer end for receiving a recessed clip member 12 formed on the periphery of the removable closure or top 13. The closure 13 may be bent to form an annular depending flange 14 that engages the inner wall of the container and provides a watertight joint between the parts.

The bottom 15 of the container is prefer-

ably supported by a spider 16 having the 55 radial arms 17, as shown in Fig. 4, and a depending gear box 18. A reinforcing band 19 preferably surrounds the container above the corrugations 20, while a similar formed band 21 of slightly wider width engages the 60 opposite end of the container and the arms 17 of the spider 16, below the corrugations 22.

Revolutely mounted in the container 10 is a metallic drum 23, having an upwardly 65 flared bottom 24, to which is suitably connected a boss 25 that has a depending skirt 26 arranged to fit over a tubular projection 27 that extends upwardly and centrally from the spider 16, as shown in Fig. 3. To permit the drum 23 to be freely rotatable on the projection 27 and also to eliminate the possibility of water escaping from the tub into the driving mechanism, hereinafter referred to, an annular bushing 28 and a packing 29 are preferably positioned between the skirt 26 and the tubular projection 27. A drive shaft 30 having a reduced polygonal portion 31 extends through a suitable opening in the boss 25 and is fastened to the 70 drum by a screw 32 that forms a watertight joint with the bottom 24.

The drive shaft 30 extends into the gear box 18, and is journaled at its opposite end to the ball-bearing member 33, rotatably supported in the recessed portion 34 of the housing 35, which housing is detachably connected to the gear box by the bolts 36.

An electric motor or any other suitable prime mover 37 is secured to the under side 90 of the spider 16 by the bolts 37', and has a pulley 38 connected to the drive shaft 30, by means of an endless belt 39 which engages a pulley 40 on the shaft 41 and then passes down over an idler pulley 42 and 95 over a pulley 43 on the shaft 44 and back to the pulley 38, as indicated in dotted lines in Fig. 3. Keyed or otherwise secured to the shaft 41 is a worm 45 which is always in mesh with a spiral gear 46 loosely mounted on the shaft 30. A bushing 47 is positioned between the spiral gear 46 and the shaft 30 so as to diminish the friction between these parts. Similarly, a worm 48 (Fig. 4) is keyed to the shaft 44 and meshes with a worm gear 49 loosely mounted on the shaft 30, and preferably separated therefrom by a bushing 50. The shaft 44 is sup-

ported by the rotatable bushings 50' carried by the bearing members 51'. The shaft 41 is similarly mounted in the gear box 18.

A double faced clutch 51 keyed or otherwise secured to the drive shaft 30 is longitudinally or axially slideable in the groove 52 formed in said drive shaft. Rigidly secured to shaft 54 is a yoke 55 (Fig. 4) provided with inwardly extending lugs 56, which engage in an annular recess 57, formed in the periphery of the clutch 51 for actuating the latter. The clutch 51 is provided with the teeth 58 and 59, arranged to selectively engage complementary teeth 60 and 61 on the adjacent faces of the gear wheels 46 and 49, respectively. While the pulleys 40 and 43 are substantially of the same diameters they are of larger diameter than the diameter of the pulley 38, so that the speed of the shafts 41 and 44 will be reduced to about one-half of that of the motor shaft. The drive shaft is preferably maintained in a fixed position relative to the means for driving it at different speeds.

The shaft 54 is connected to an operating lever 62 (Fig. 4), which is held in different positions by means of a bracket 63 having a depending arm 64 preferably provided with three notches 65, 66 and 67, as shown in Fig. 1, for maintaining the clutch 51 and its associated parts in the neutral, washing, or drying position. A spring 68 may be confined between the shaft 54 and the bracket 63, so as to create a rotating strain on the shaft 55 and thus assist the lever 62 when moving the clutch from one position to another.

In order that the washing machine may be maintained in an inclined position, such as shown in Fig. 1, during the washing operation and be conveniently moved to a vertical position for the drying operation, as shown in Fig. 2, a support, which is bodily movable with the container 10, is provided. This support, which may assume various forms, is shown in Figs. 1 and 2, as comprising a substantially U-shaped member 69 connected to the forward portion of the container by the bolts 70. A similarly formed member 71 is secured to the spider 16, and has journaled thereon a transverse rubber roller or caster 72, as shown in Fig. 4. The arms of the members 69 and 71 are preferably connected by the brace bars 72'. It will be seen that by reason of this support, the machine 10 can be with facility operated on the ground, or, if desired, may rest on a washtub, stand, or the like; such as 73, as shown in Fig. 1. Preferably, a board 73' is mounted on the tub for supporting the machine thereon.

In order to lessen the strain of the weight of the drum when in the inclined washing position, the cover 74, which closes the central openings in the closure 13 and drum 23,

is provided with an extending portion 75 arranged to contact with the adjacent beaded surface 76 of the drum 23, and support the same during the operation of the machine. The cover 74 is preferably provided with a curved flange 77, which engages an annular bead 78 on the closure 13, in such a manner as to permit the same to be readily removed from the container, but when in the closed position, to form a watertight connection of the parts.

To prevent the clothes from balling up during the operation of the machine, thimbles or projections 79 are connected to the inner wall of the drum 23, and are preferably arranged in a vertically inclined position relatively to each other, so as to separate and loosen the clothes.

The operation of the machine is as follows:—

Assuming the articles to be washed to be in the drum 23, and the necessary amount of water within the container 10, and the clutch 51 in the neutral position, as shown in Fig. 3, the cover 74 is placed in position and the machine is swung about its horizontal axis on the roller 72, to take the position as indicated in Fig. 1. The motor is turned on and the lever 62 moved to cause the clutch 51 on the drive shaft 30 to engage the teeth on the worm gear 49, which will rotate the drive shaft 30 and the drum 23 at a speed of about twenty-five (25) revolutions a minute. When the clothes have been thoroughly washed, the support and the container are moved in the direction of the arrow, as shown in Fig. 1, to assume the drying position indicated in Fig. 2. The lever 62 is then actuated to cause the clutch 51 to be brought out of engagement with the worm gear 49 and to engage with the teeth on the spiral gear 46, thus causing the drive shaft 30 and its associated parts to rotate at about four hundred (400) revolutions a minute. Due to the speed of rotation of the drum 23, the water therein is whirled upwardly and escapes through the perforations 80 adjacent the upper portion of the drum. Preferably two rows of these perforations are provided, so that, the water may escape from the drum 23 into the container 10 during the drying operation, without the necessity of first draining the same from the drum.

After the clothes have been thoroughly dried, they may be readily removed from the drum upon disengaging the cover 74 from the closure 13. The idler pulley 42 is preferably adjustably connected to one of the arms 17, of the spider by a threaded bolt 81, and nuts 82 and 83, as shown in Fig. 4, so that the belt 38 may be maintained at all times in tight engagement with the pulleys.

In the modified form of the invention illustrated in Fig. 5, the closure or top

84 which at its outer periphery is formed the same as the closure 13 shown in Figure 3 has an annular bead 85 which receives a yieldable clip portion 86, of 5 the cover 87, so as to detachably secure the latter in position; additionally, the cover 87 has a cupped or dished portion 88 bent to form an annular recess 89, in which is journaled the tapered rollers 90 that engage the 10 adjacent surface of the beads 91 on the rotatable drum 92, so as to reduce the friction of the parts during the operation of the machine.

In the form of the invention shown in 15 Fig. 6, the outer closure for the container and the drum or perforation is made out of a single piece, and consists essentially of a closure or top 93, having a central opening 94 and a yieldable clip 95 in its outer periphery, which clip is arranged to engage a bead 96 on the container 97 and provides a water tight joint when in the closed position. The central opening 94 is preferably struck-out from the cover to form an inwardly projecting annular flange 98 having a stop 99 that abuts against an annular bead 100 on the rotatable drum 101.

In the form of the invention illustrated in Figs. 7 and 8, the casing 102 has one side 30 bulged out as at 103, which, in addition to acting as a stop or support for the machine when the same is in an inclined position, also tends to increase the capacity of the container. A U-shaped support 104 having 35 a transverse roller 105, is connected to the bottom of the container in the manner as previously described, and acts as a fulcrum, about which the machine is moved from the washing to the drying position. A removable cover 105 is arranged to close the opening in the top of the container, and also acts as a support for the rotatable drum, while a motor 106 and the clutch operating handle 107 is associated with the machine in the 40 same manner as the motor 37, and the operating handle 62 previously referred to.

In the modification illustrated in Fig. 9, the cover 109 has an annular yieldable clip 110 arranged to detachably engage the bead 111 upon the closure 112 so as to form a water tight joint between the parts, the outer periphery of the cover 112 being formed substantially the same as the covers 13 and 84, previously described. The cover 109 extends through the openings in the container 112 and the rotatable drum 113, but the portion of the cover which projects into the drum is preferably spaced therefrom, so as to act as a closure for preventing the articles being treated from falling out of the drum, and provide a small passage between the cover and the annular bead 114 on the drum, so that fluid may pass therethrough.

It will be seen, by reason of the present 45 construction, a washing machine is provided,

which is admirably suited for use in small apartments and places where limited space is available. Moreover, the machine being light and portable may be easily moved from place to place, and is of such a size, 70 that when not in use, will not occupy much space.

It is understood that the form of the invention herewith shown and described is merely illustrative, and in no sense restrictive, and that such changes as fall within the purview of one skilled in the art may be made without departing from the spirit of the invention and the scope of the claims.

I claim:—

1. In a machine of the class described, the combination of a tiltable container having an opening in one end thereof, said container adapted to assume a substantially inclined position during the washing operation and a substantially horizontal position during the drying operation, a rotatable drum in the container having an opening aligning with the opening in the container, a motor operatively connected to the drum, a closure fitting in said openings, means journaled in the wall of said closure and adapted to engage said drum and act as a support for the same when the machine is in either the washing or drying position.

2. A machine of the class described having in combination a tiltable container adapted to assume an inclined washing position and substantially a horizontal drying position, a drum revolvably mounted in the container, means for actuating said drum, a support connected to one end and a side of the container, said support being offset laterally relative to the container, and a member rotatably mounted on said support 105 and about which the machine may be moved to either the washing or drying position.

3. A washing machine of the class described having in combination a tiltable container provided with a ground engaging portion extending from the bottom thereof, a drum revolvably mounted in the container, a motor operatively connected to said drum, a support extending from the side of the container and connected thereto for maintaining the machine in its inclined washing position, said support coacting with the ground engaging portion for supporting the machine in its drying position, and a revolute member connected to said support for moving the machine to different positions.

4. In a machine of the class described, the combination of a tiltable container having an open top, a closure for said top provided with a central opening, said container adapted to assume a substantially inclined position during the washing operation and a substantially horizontal position during the drying operation, a revolute drum in the container having an opening aligned

with the opening in said closure, and a cover fitting in said openings and engaging said drum for supporting the same when the machine is either in its washing or drying position.

5. In a machine of the class described, the combination of a tiltable container having an open top, a closure for said top provided with a central opening, said container 10 adapted to assume a substantially inclined position during the washing operation and a substantially horizontal position during the drying operation, a revolute drum in the container having an opening aligned

with the opening in said closure, a cover fitting in said openings and engaging said drum for supporting the same when the machine is either in its washing or drying position, a support connected to one end and a side of the container and offset laterally 15 relatively thereto, and a revolute member journaled to said support and about which the machine may be moved to different positions.

In testimony whereof I have hereunto set my hand.

THOMAS J. McDONALD.
